GAS STOVE

John E. Chambers, Shelbyville, Ind.

Application August 10, 1931, Serial No. 556,235

8 Claims. (CL. 126—39)

My invention is concerned with gas ranges, particularly with gas ranges of the console type, and it is my object to arrange the gas-valve controlling members of the range in such a manner as to increase the convenience of operation and enhance the appearance of the range. A further object of my invention is to produce a compact arrangement of the gas-valve controlling mechanism of the range.

10 In carrying out my invention I group the gas-valve controlling members associated with a plurality of gas-valves of the range, preferably mounting them on a common axis at the front of the range in close juxtaposition in order that the relative condition of adjustment of such controlling members may be readily apparent. Conveniently, the gas-manifold extends along one side of the range, the branch gas-pipes extending vertically therefrom, and the gas-valves in such pipes being disposed with their axes parallel to each other and to the common axis of the gas-valve controlling members.

25 The accompanying drawings illustrate my invention: Fig. 1 is a fragmental front elevation of a gas-range; Fig. 2 is a fragmental end elevation with parts of the range broken away to the line 2—2 of Fig. 1 to illustrate more clearly the details of construction; and Fig. 3 is a horizontal section through the range on the line 3—3 of Fig. 2.

30 The range illustrated in the drawings has a flat cooking top 10, end walls 11, a front wall 12, and a back wall 13. The arrangement of the burners in such a stove may be anything desired. I have shown in the drawings three burners 15, 16, and 17, the burners 15 and 16 being shown as disposed immediately below the cooking top 10, while the burner 17 is shown as located in the bottom of an insulated cooking compartment 18 which will be described in greater detail herein-after. Wherever the burners with which my invention is associated may be located in the stove, they are individually supplied with fuel, usually gas, by means of pipes 20 which lead from a common manifold 21 adapted to be connected to any desired fuel-source.

35 As previously indicated, the manifold 21 is preferably disposed in horizontal position at one end of the range, the various branch-pipes 20 leading vertically from it. In each of the branch-pipes 20 there is located a control valve 22, these valves having rotatable valving elements disposed on axes parallel to each other and to the front-wall 12 of the range. The valve members of the valves are provided with extensions 23

which project inwardly from the valves and are supported at their inner ends in a suitable cross-member 24.

40 The valve-controlling members 26 are pivotally mounted on a common axis at the front of the range. As is clear from the drawings, this pivot-5 al mounting is provided by a rod 27 which extends horizontally transversely of an opening 28 in the front wall 12 of the stove, being secured to such front wall by means of bolts 29. A cover 10 30 normally closes the opening 28 in the front wall 12 of the range, the cover 30 being provided with a central opening through which the operating handles 26 project. The cover 30 may be held in place by providing at its lower edge a 15 down-turned lip 31 and at its upper edge a screw 32. When the cover 30 is in place, the lip 31 is engaged behind the lower edge of the opening of the front wall 12 of the stove, and the screw 32 passes through a hole in such front wall and is 20 retained by a nut 33 accessible through the cooking top.

45 Each of the control handles 26 has secured to it at an eccentric point a rearwardly extending rod 35, the rods 35 being respectively connected to the extensions 23 of the valving members of the valve 22. To this end, each of such extensions 23 carries rigid with it an arm 36 in the outer end of which a pin 37 is pivotally mounted. The pins 37 are respectively provided with trans-30 verse screw-threaded openings for the reception of the rear ends of the rod 35. The arms 36 on the extensions 23 are mounted in staggered relation in order that the rods 35 may be disposed generally parallel to each other, as is clear from 35 Fig. 3. By attaching the rods 35 to the arms 36 through screw-threads, the effective lengths of the arms can be varied to bring all the control members 26 into the same plane when the valves 22 are closed.

50 With the valve-control members 26 disposed in vertical position as illustrated in full-lines in the drawings, all valves are closed. To open any valve, its associated control handle 26 is swung upward to or toward the position illustrated in 45 dotted lines in Fig. 3. This movement of the control member is communicated through the associated rod 35, arm 36, and extension 23 to the valve member of the valve which it is desired to open. Each valve may be independently controlled, and the condition of any valve is apparent at a glance. If any valve is open, its controlling member 26, projecting forwardly out of the plane of the remaining control members, is 55 conspicuous.

For the purpose of facilitating removal of any of the valves 22 the extension 23, while rotatable with the valving elements, are arranged to be readily detachable therefrom. To this end each 5 valving element and its associated extension are provided with interengageable means for insuring their joint rotation, such means being disengageable by axial movement of the extension. Springs 37, acting between the cross-member 24 and abutments 38 on the extensions 23 serve normally to hold the extensions in engagement with the valving elements; but any extension can readily be disengaged from its associated valving element when the valve is to be removed.

As previously indicated, the burner 17 is located at the bottom of an insulated cooking compartment 18. This compartment has an opening for the reception of the burner 17 and in its rear wall a ventilating opening 40. A removable cover 41 is provided for the open top of the compartment 18. The opening 40 has associated with it a damper or valve 42 which is preferably jointly operable with the valve 22 that controls the burner 17. To this end, the burner 42 may be pivoted on a horizontal axis below the opening 40 and provided with an arm 43 which extends generally downward below the axis of such pivotal mounting. The lower end of the arm 43 is connected by a link 44 to the arm 36 on the extension 23 of the valve member of the valve 22 which controls the supply of gas to the burner 17.

With the arrangement just described, the damper 42 will be closed whenever the burner 17 is not in use. When the burner 17 is in use, 35 the valve 22 associated with it will be open as the result of upward movement of the corresponding control member 36. The interconnection of the arm 43 with the rotatable member of the valve which controls the supply of fuel to the burner 17 insures that the damper 42 will also be open in order that products of combustion from the burner 17 may escape. When the burner 17 is turned off by downward movement 40 of the handle 26, the damper 42 will be closed to prevent the circulation of air through and the consequent loss of heat from the compartment 18.

I claim as my invention:—

1. In a gas range having a plurality of burners, pipes for supplying gas to said burners, a valve in each of said pipes, each of said valves having a rotatable valving element and said valves being disposed with the axes of said valving elements parallel, and a control member for each of said valving members, said control members being pivotally mounted in juxtaposition on a common axis.

2. In a gas range having a plurality of burners, pipes for supplying gas to said burners, a valve in each of said pipes, each of said valves having a rotatable valving element and said valves being disposed with the axes of said valving elements

parallel, a control member for each of said valving members, said control members being pivotally mounted on an axis parallel to the axes of said valving elements, each of said valving elements having an operating arm, said control members and said arms being correspondingly axially spaced, and a link operatively connecting each of said control members with the operating arm of the associated valve, said links being adjustable in effective length.

3. In a gas range having a plurality of burners, pipes for supplying gas to said burners, a valve in each of said pipes, each of said valves having a rotatable valving element and said valves being disposed with the axes of said valving elements parallel, a control member for each of said valving members, said control members being pivotally mounted on an axis parallel to the axes of said valving elements, each of said valving elements having an operating arm, said control members and said arms being correspondingly axially spaced, and a link operatively connecting each of said control members with the operating arm of the associated valve.

4. The invention set forth in claim 1 with the addition of a manifold disposed horizontally at one end of the range, said pipes extending vertically from said manifold and said control members being mounted at the front of the range.

5. The invention set forth in claim 3 with the addition of a manifold disposed horizontally at one end of the range, said pipes extending vertically from said manifold and said control members being mounted at the front of the range.

6. In a gas range having a plurality of burners, means for supplying gas to said burners, said means including a valve for each burner, and a control member for each of said valves, said control members being pivotally mounted in juxtaposition on a common axis at the front of the range.

7. In a gas range having a plurality of burners, means for supplying gas to said burners, said means including a valve for each burner, and a control member for each of said valves, said control members being pivotally mounted in juxtaposition on a common axis.

8. In a gas range having a cooking top, an insulated compartment beneath said cooking top, a burner for said compartment, a valve for said burner, said compartment having an open top and a ventilating opening, a closure for said open top, a damper for said opening, said valve having a rotatable valving element, a control member, said control member and said damper being pivotally mounted on axes parallel to that of said valving element, a link operatively interconnecting said control member and valving element, and a second link operatively connecting said valving element and damper.

JOHN E. CHAMBERS.
